No. 653,589.

Patented July 10, 1900.

J. L. OSWALT.

THIN PLACE DETECTOR FOR LOOMS.

(Application filed Feb. 27, 1900.)

(No Model.)

UNITED STATES PATENT OFFICE.

JOHN L. OSWALT, OF SPRAY, NORTH CAROLINA, ASSIGNOR TO THE DRAPER COMPANY, OF PORTLAND, MAINE, AND HOPEDALE, MASSACHUSETTS.

THIN-PLACE DETECTOR FOR LOOMS.

SPECIFICATION forming part of Letters Patent No. 653,589, dated July 10, 1900.

Application filed February 27, 1900. Serial No. 8,687. (No model.)

To all whom it may concern:

Be it known that I, JOHN L. OSWALT, of Spray, county of Rockingham, State of North Carolina, have invented an Improvement in

5 Thin-Place Detectors for Looms, of which the following description, in connection with the accompanying drawings, is a specification, like characters on the drawings representing like parts.

10 In weaving cloth thin places or streaks result from the continued operation of the take-up mechanism after failure of the filling or its exhaustion in the shuttle, and it sometimes happens that the filling-fork fails to 15 operate properly for various reasons, so that in the case of an automatic loom, for instance, a change of filling will not be effected at the proper time, resulting in a bare or thin streak in the cloth. It is manifestly of im- 20 portance that the loom be stopped promptly if anything of this nature occurs in order that the operative can wind back the cloth and repair the faulty work.

This invention has for its object the pro- 25 duction of means for detecting the occurrence of a bare or thin place in the cloth and automatically effecting the stoppage of the loom promptly.

Figure 1 is a cross-sectional view of a portion of a loom with one embodiment of my 30 present invention applied thereto. Fig. 2 is a perspective detail showing the thin-place detector and its connected drop member in normal inoperative position. Fig. 3 is an 35 enlarged longitudinal sectional view of the cloth at the fell or cloth-forming point, showing the thin-place detector supported by the filling; and Fig. 4 is a similar view, but with the detector in operative position, due to occurrence of a thin place.

The loom-frame A, breast-beam A¹⁰, lay A⁸, and harnesses H may be of usual construction, the cloth M^X being taken up as formed by suitable take-up mechanism. (Not shown.)

40 I have herein shown warp-stop-motion mechanism comprising drop members a, longitudinally slotted to receive the warp-threads and strung upon a cross-bar a^X, Fig. 1, flat bars b b' guiding the drop members in their 45 vertical movements, normal warp-threads maintaining the drop members inoperative

in well-known manner—such, for instance, as shown and described in United States Patent No. 545,728, dated September 3, 1895. Stopping mechanism for the loom is provided, 55 including the usual shipper-lever S and belt-shifting means, (not shown,) the shipper-lever being released by a knock-off arm e', fast on a rock-shaft e, mounted in the loom-frame and rocked, as will be described. When a 60 warp-thread fails, its drop member a moves down into the path of a feeler f, mounted on arms f' of a rock-shaft f², Fig. 1, which is normally vibrated in suitable manner, such engagement of the drop member and feeler 65 acting through intervening devices to rock shaft e and knock off the shipper-lever.

On a suitable part of the loom-frame, as the arch A^X, Figs. 1 and 2, I have mounted a bracket b⁵, having ears b⁶ to receive a substantially-horizontal rock-shaft or light rod b⁷, parallel to the vertical plane of travel of the warps and provided with two inwardly-extended arms b⁸ b⁹, the former herein shown as projecting above one end of the series of 70 drop members a and the latter projecting over the cloth M^X above the fell. Herein the arm b⁹ is shown as bent down at b¹⁰ to rest upon the cloth adjacent the fell, the lower end of the thin-place detector b¹⁰ being preferably flattened to form a thin blade b¹², Figs. 3 and 4, lying parallel to the warps and resting on the filling-threads t at the fell. A thin flat drop member b¹⁵ is shown as jointed at b¹⁶ to the arm b⁸ and depending between the 75 guide-bars b b', Fig. 1, at one end of the series of drop members a, the lower end of the member b¹⁵ being normally maintained up out of the feeler-path so long as the filling sustains the detector b¹⁰. In Fig. 2 the member b¹⁵ is 80 shown as longitudinally slotted to receive the fixed cross-bar a^X, which extends across the loom, as usual. When, however, the filling fails and is not beaten up, the take-up draws the cloth along, so that the detector b¹⁰ will 85 be no longer supported and its thin foot b¹² drops down between the warp-threads, as in Fig. 3, detecting the thin or bare place formed in the cloth. At the same time the shaft b⁷ rocks and the drop member b¹⁵ descends into 90 position to engage the feeler f of the warp stop-motion, and the operation of the stopping 95 100

mechanism is effected as it would be had a warp-thread failed, and the loom is stopped, the operative knowing the trouble to be with the filling, owing to the abnormal position of 5 the arm b^9 . Collars 20 on the rock-shaft b^7 prevent endwise movement in its bearings on the bracket b^5 . As soon as the loom is stopped the operative winds the cloth back to the proper point, resets the thin-place-controlling 10 means for the stopping mechanism, attends to renewal of the filling, and starts the loom up again at the proper pick, and a thin streak in the cloth is obviated.

The feeler may be vibrated by any suitable 15 mechanism—such, for instance, as is shown in United States Patent No. 621,310, granted March 14, 1899—a link f^4 , jointed to an arm f^3 on the rock-shaft f^2 , having a toe f^x to travel on a cam F^X on the cam-shaft C of the 20 loom, said link having a bunter f^5 to be engaged by a tappet m on the tappet-cam M , Fig. 1, when the feeler f is arrested. An arm e^2 on the rock-shaft e is pivotally connected with a link e^4 , hooked around the cam-shaft 25 C at e^5 and having jointed to it at e^7 a lever e^8 , provided with a stud e^9 , extended through a slot f^8 in the depending end of the link f^4 . Adjustment of the bunter f^5 relative to the tappet-cam is effected by a rod e^{10} , adjustably 30 connecting the lever e^8 and arm e^2 , as in the patent referred to. When the feeler is arrested, the bunter is held in the path of and is engaged by the tappet-cam M , and the link e^4 is moved longitudinally to rock the shaft e 35 and release the shipper-lever.

My invention is not restricted to the construction and arrangement herein shown, as I have shown one practical embodiment of my invention without attempting to show or describe the various modifications which can be made without departing from the spirit and scope of my invention.

Having fully described my invention, what I claim, and desire to secure by Letters Patent, is—

1. In a loom, stopping mechanism therefor, a series of warp-stop-motion detectors maintained inoperative by normal warp-threads, a thin-place detector, and means controlled 45 thereby and operatively connected with the

stopping mechanism to effect the operation thereof upon occurrence of a thin place in the cloth.

2. In a loom, stopping mechanism therefor, a series of warp-stop-motion drop-detectors 55 maintained inoperative by normal warp-threads, a thin-place detector normally held inoperative by the filling at the fell of the cloth, and a drop member operatively connected therewith and located in the series of 60 drop-detectors, to effect the operation of the stopping mechanism upon failure of the filling at the fell.

3. In a loom, stopping mechanism, including a vibrating feeler, and a series of drop 65 members to coöperate with the feeler and effect the operation of the stopping mechanism, and means operatively connected with one of said members to normally maintain it inoperative by or through the presence of filling at the fell of the cloth, the other drop members being maintained inoperative by normal warp-threads, engagement of any of said drop members with the feeler effecting the operation of the stopping mechanism. 70

4. In a loom, stopping mechanism, means controlled by the warp-threads, and means controlled by or through the presence of the filling at the fell of the cloth, both of said means being adapted to coöperate with the 80 stopping mechanism to effect the operation thereof by warp failure and absence of filling at the fell, respectively.

5. In a loom, a rock-shaft having attached arms, a thin-place detector depending from 85 one arm to normally rest on the cloth adjacent the fell, a drop member depending from the other arm, and stopping mechanism for the loom, including a vibrating feeler, the detector descending upon occurrence of a thin 90 place in the cloth and positioning the drop member to engage the feeler and thereby effect the operation of the stopping mechanism.

In testimony whereof I have signed my name to this specification in the presence of 95 two subscribing witnesses.

JOHN L. OSWALT.
